METHOD AND APPARATUS FOR SPRAYING
CONTAINERS

John F. Peters, Leonia, N. J., assignor to American Can Company, New York, N. Y., a corporation of New Jersey

Application May 19, 1934, Serial No. 726,550

9 Claims. (Cl. 91—45)

The present invention relates to the spraying or coating of containers or cans and has particular reference to coating with paraffin or other like material which is solid at ordinary room temperatures and which can only be applied while heated and while in liquid form, the coating material solidifying upon cooling to form a continuous lining for the inside of the can.

The present invention contemplates preheating a can and while in heated condition spraying its interior with paraffin in liquid form, which is maintained as a liquid in a supply reservoir, and which is conducted to and discharged from a spray head located inside of the can. During the spraying action the can is preferably moved relative to the spray head and the lining material is thus evenly deposited on the interior of the can, the paraffin or other coating material being maintained in its liquid form during the entire spraying action.

The discharge of coating from the spray head is regulated and controlled so that only the proper amount of paraffin is ejected from the spray head and this only when the can is in proper position to receive it. Following the spraying operation the coating material may be set or solidified by cooling of the can while rotating it on its longitudinal axis or otherwise so that the resulting lining or coating will be even and uniform in all sections.

An object of the present invention is the provision of a method of and apparatus for coating a can which comprises preheating the can and positioning it to receive a coating material; heating the coating material to keep it in liquid condition and while so conditioned projecting it onto the desired can area which is thereafter cooled in order to set the coating.

Another object of the invention is the provision of such a method wherein heated air under pressure is introduced into the coating material and is utilized in a spraying action and this heated air is further used in maintaining the spraying parts clear during the interim between spraying operations.

A further object of the invention is the provision of a method of the character described for coating a can wherein the can is moved while it is being coated to insure even distribution of the coating material, and is then rotated while it is being cooled to insure uniform setting of the coating material in an even thickness on the can walls.

A further object of the invention is the provision of a heating system in a spraying and coat-

ing machine for keeping paraffin or other like substance in heated and liquid condition during its passage from a reservoir in the machine to the point of its ejection.

Another object of the invention is the provision of a heating system of the character described which heats both coating material and compressed air which are brought together or mixed and in this form are ejected as a spray.

Yet another object of the invention is the provision of such an apparatus for the coating of the inside of a nozzle can which has only a restricted nozzle opening the coating material being ejected from a spray head extending through the nozzle and positioned within the can, there being a relative movement between can and spray head during the coating operation, this feature insuring an even distribution of the coating material upon the can area being coated.

A still further object of the invention is the provision of a control for the ejection of coating material from the spray head of a coating machine which insures a discharge of the material in time with the positioning of the can for coating.

Numerous other objects and advantages of the invention will be apparent as it is better understood from the following description, which, taken in connection with the accompanying drawings, discloses a preferred embodiment thereof.

Referring to the drawings:

Fig. 1 is a side view of a can preheating oven used in carrying out the first step of the instant invention;

Fig. 2 is a side view of a can spraying machine utilized in a further step of the invention;

Fig. 3 is an end view partly broken away of an air cooling machine for cooling cans treated by the present invention method;

Fig. 4 is a plan view on an enlarged scale of the can spraying machine of Fig. 2;

Fig. 5 is a sectional view of the machine taken along the line 5—5 in Fig. 4 and also showing a wiring diagram embodying an electric connection;

Fig. 6 is a sectional view of the can holding device of the same as taken along the line 6—6 in Fig. 5;

Figs. 7 and 8 are fragmentary views of certain of the can holding and can rocking devices;

Fig. 9 is a fragmentary sectional detail of a can and a spray head;

Fig. 10 is a sectional view taken through the can spray head and associated parts showing on

a larger scale and in greater detail a part of the same elements that are shown in Fig. 5; and

Fig. 11 is an enlarged transverse sectional detail of the spray head stem as viewed along the line 11—11 in Fig. 10.

For the purpose of illustrating the carrying out of the various steps of the instant method on one form of container or can there is illustrated in the drawings a can A of square or oblong shape having a closed bottom and a partially closed top end which carries a nozzle B. In the description that follows this type of can will be carried through the various operations of coating which broadly include successively subjecting the can to the preheating oven, to the can spraying machine and to the can cooling machine, these three machines being disclosed in the respective Figures 1, 2 and 3 of the drawings.

Uniformly coating the interior of a can of this type is more difficult than would be the coating of the ordinary round or more open type of can and therefore by showing how such a can is handled it will be obvious that the more simple types are equally adapted to such treatment.

The can preheating oven of Fig. 1 comprises a table 21 supported by a frame 22 over which the cans A are conveyed by a chain 23 having spaced can propelling lugs 24. The chain operates over a drive sprocket 25 and idler sprocket 26 respectively mounted on a drive shaft 27 and an idler shaft 28, these shafts being journaled in the table frame 22. The drive shaft 27 may be driven in any suitable manner at a speed which will permit the cans to be heated during their passage over the table to about the temperature of the heated coating material which is subsequently applied in the spraying machine of Fig. 2.

A hood 31 is mounted on the table 21 and provides a pass for the cans A moving over the table. It is this hood which forms the oven proper and its interior is heated in any suitable manner as by gas flames discharged through a series of gas jets 33 located below the hood which are connected to a gas supply line 35. The cans A after being heated are taken off of the discharge end of the table 21 in any suitable manner and are transferred to the spraying or coating machine of Fig. 2 which will next be considered in some detail.

The stationary and operating parts of this machine are mounted on a base housing 41 which supports side brackets 42, 43 (Figs. 4, 5 and 6), each bracket at its upper end being formed with spaced bearings 44, the two bearings of each bracket being in horizontal alignment and providing a sliding support for a horizontal slide shaft 45 which extends out in front and to the rear of the brackets.

A can support cradle 46 is carried on the forward ends of the two slide shafts 45. The can cradle comprises a pair of spaced holding plates 47 (Figs. 4 and 6) and a pair of spaced support saddles 48. Both plates and saddles may be slightly longer than the height of the can A which they support and are shaped and located to receive and hold the can with two of its opposite corners in a vertical line and the other two corners in a horizontal line as best shown in Fig. 6.

The plates and saddles closely fit the adjacent walls of the can when the latter is placed in the cradle of the spraying machine. For a can

having the shape disclosed the plates 47 are formed with opposed curved pockets 49 which receive the horizontally disposed corners of the can and the saddles 48 are located at an angle and together form a trough which nicely fits the can's side walls adjacent its lower corner.

The saddles 48 are mounted on a transverse support rod 51 the ends of which are threaded and clamped in lower clamp blocks 52. Each block is suspended on the lower end of a vertical rod 53 and each rod is carried in a shift block 54 (Figs. 6 and 7) the two vertical rods 53 depending from the two shift blocks which are arranged on opposite sides of the can cradle 46.

Each shift block is pivotally mounted on a stud 55 which is carried in and which projects laterally from a support member 56. Each of the latter is threaded and clamped on the forward end of its slide shaft 45.

In a similar manner, each plate 47 is carried on and pinned to the inner end of a short shaft 57, these two shafts extending in toward each other from their threaded and clamped connections with clamp blocks 58 carried on the vertical support rods 53 midway of their lengths.

When the heated can A has been removed from the preheating oven of the preceding machine just described, it is placed in the spraying machine cradle 46 where it rests in the plates 47 and on the saddle members 48. At such a time the cradle is in a forward position, that is, pulled out in the front of the machine with the slide shafts 45 extended forward to their extreme sliding limits.

The horizontal slide shafts 45 are held together in the rear by a cross head 59 (Figs. 4 and 5) the ends of which are clamped in position by nuts threaded engaging the shafts. This insures unit movement of the shafts, the can support cradle and all parts carried on the shafts and cradle. The cradle 46 is moved into its can receiving position by sliding of the shafts and this shaft movement is cam actuated in synchronism with the operations of the machine.

Each shift block 54 carries a stud 60 (Figs. 4, 6, 7 and 8) which forms a pivotal connection for the forward end of a connecting rod 61. The rear ends of the two connecting rods are pivotally connected at 62 to the upper ends of lever arms 63 (see also Fig. 5) which are pinned, one at each side of the machine, to the ends of a horizontal rock shaft 64. Shaft 64 is supported for rocking movement in bearings 65 formed in the side brackets 42, 43.

An actuating arm 66 is also pinned to the rock shaft 64 intermediate the bearings 65 and is pivotally connected at 67 to the end of a yoke 68, the fork ends 69 of which extend over and straddle a slide block 70 mounted on a drive shaft 71. Collars 72 are pinned to the shaft and are located on opposite sides of the block and these prevent side movement of the latter during the rotation of the shaft.

The drive shaft 71 is journaled in a suitable bearing formed in a bracket 73 which is bolted to the base housing 41. This shaft constitutes the main drive shaft of the machine and may be rotated in any suitable manner as by the application of rotation to a gear 74 mounted on and pinned to one end of the shaft. Since the operation of a machine of this character may be carried out in many well known and satisfactory ways no further description will be attempted on this point other than indicating in Fig. 2 a control foot clutch treadle 75 by means of which

an operator may start the machine for each cycle of its operation.

The drive shaft 71 also carries a face cam 76 which is formed with a cam groove 77 in which 5 a cam roller 78 operates. Roller 78 is rotatably mounted on a stud 79 carried in the yoke 63 and during one complete rotation of the cam with the drive shaft the cam groove 77, operating against the roller 78, slides the yoke back and 10 forth so that the slide shafts and the can cradle are moved first into forward position for receiving a can to be sprayed and for removal of a sprayed can and then are moved back into a rear position during the spraying operation.

15 The can cradle 46 besides having this forward and back movement with the slide shafts also has a rocking movement during which movement the shift blocks 54 and parts carried thereby are pivoted on the studs 55. This pivoting action 20 takes place on both the forward and rear movement of the shafts. It provides for more even coating as will be again referred to hereinafter. In the rocking movement when the shafts 45 are slid forward by the forward travel of the connecting rods 61 these shift blocks are moved clockwise from the position illustrated in Fig. 7 25 into that shown in Fig. 8. Provision is made for limiting such shifting movement.

For this purpose each support member 56 is 30 formed with a vertical extension 85 (Figs. 4 and 6) in the upper part of which a pin 86 is mounted. The pin 86 projects laterally from the member and extends through a slot or opening 87 (Figs. 7 and 8) formed in its associated shift block 54. 35 Each shift block carries set screws 88, 89 which are disposed on the opposite ends of the slot. The ends of these screws strike against the stop pins 86 and this limits the rocking movement of the blocks, the can support cradle and the can 40 carried thereby.

In the inserted position of a can A within the can support cradle 46 the nozzle B of the can is in horizontal alignment with a spray head 95 (Figs. 5 and 10). This spray head is held in 45 fixed position and as the cradle is moved back by the sliding of the shafts 45 just described, the can is moved over the spray head.

In this rearward movement the cradle and can are first brought into the level or horizontal 50 position and then the can passes over the outer end of the spray head and into the spraying position of Figs. 5 and 10. During the entire backward movement of the can it remains substantially horizontal with the shift blocks 54 in the 55 position shown in Fig. 7.

The spray head 95 is a complex unit and is 60 for the most part enclosed within a hollow shell stem or tube 96 (Figs. 10 and 11). The rear end of this tube is tightly confined within a web 97 formed in the center of a vertical column 98 which is mounted on the base frame 41 and located between the side columns 42, 43.

The head accommodates not only heated paraffin or other coating material but also the proper 65 tubes and passages for compressed air which is used with the liquid paraffin during the spraying operation. In addition there is space for a heating fluid which in the present embodiment is water. The coating material, the air and the heating fluid will next be considered in this order in connection with such parts of the machine as are directly involved in handling these elements.

70 The column 98 indirectly supports the res-

ervoir for the paraffin and a rear bracket 105 (Fig. 5) is also mounted upon the cover 99 of the tank 101 for this purpose. Column and bracket directly support a tank 106 which is formed with an opening in its top.

The paraffin is contained within a smaller tank 107 which closes the top opening of the tank 106 and which constitutes the paraffin reservoir. This smaller tank is formed with an upper flange 108 by which it is supported and which rests on the top of the tank 106. The paraffin reservoir is closed at its top by an airtight cover plate 109 which is bolted to its flange 108, a gasket 110 being interposed between the cover and the flange and forming an airtight seal. A liquid 15 paraffin may be supplied to or emptied from the reservoir 107 through a supply pipe 111 controlled by a service valve 112, this pipe passing through a stuffing box 113 carried in the wall of the tank 106. Or the solid paraffin may be first put into 20 the reservoir by removal of the cover plate 109.

The liquid paraffin for the spray is drawn from the reservoir through a vertically disposed tube 114 which extends down from the reservoir tank inside of the column 98. The lower end of the tube is threadedly engaged in the web 97 (see Fig. 10) as shown at 115.

A vertical passageway 116 cut through the upper part of the web 97 communicates at its top with the lower end of the tube and provides a further passage for the paraffin. The part of the tube or shell 96 of the spray head which extends into the column web is perforated on top as at 117 and this opening, communicating with the passageway 116, permits an unrestricted flow 30 of the liquid paraffin into the spray head.

The tube 96 (Figs. 10 and 11) is divided into an upper and lower chamber by a horizontal partition 121 which extends nearly the length of the tube but this partition terminates just short of the forward end.

The rear end of the tube is closed by a disc 122 and an inclined partition 123 joins with or is an integral part of the horizontal partition 121. 45 These partitions cooperating with the walls of the tube close off an upper rear chamber 124 in the rear of the spray head. This chamber receives the paraffin passing from the tube 114 and passing through the passageway 116 and the opening 117.

An upper horizontal paraffin pipe 131 is disposed within the upper part of the spray head and rests upon the partition 121. The rear open end of this pipe passes through the inclined partition 123 and extends into the chamber 124. By means of this pipe the paraffin is conducted from the chamber 124 to the forward end of the spray head.

Spray head 95 is formed with a head sleeve 132 which is carried on the forward end of the tubular shell 96, the parts being tightly joined to one another in a hermetic connection. A spray discharge tip 133 is threadedly secured in the head sleeve 132 and is preferably formed as a double spherical terminal formed in two sections. Both 60 sections are hollow and enclose a spray chamber 135. Perforations 136 are formed in the spherical tip and through these perforations the coating material mixed with air is atomized and ejected for the spraying operation.

The spray chamber 135 is connected by a passageway 137 to a mixing chamber 138 formed in the sleeve 132. The forward open end of the paraffin pipe 131 extends into this chamber. The paraffin pipe 131 functions not only as a pas- 70 75

sage for the paraffin but its forward end cooperates with a bulb-like valve 145 which is secured to the forward end of a valve stem 146 which extends through the pipe. The rear end of the 5 valve stem passes through the rear chamber 124 and out through the disc 122 in the end of the tube. The valve stem further extends through a body 147 and a gland 148 of a stuffing box which is secured on the rear face of the disc 122.

10 When the valve stem is drawn back the bulb valve 145 is seated in the forward end of the paraffin pipe 131 and this closes off flow of paraffin into the mixing chamber 138. The operation of this valve and the shutting off of the paraffin 15 supply is associated with an electric actuating device which synchronizes the spraying operation with the movement of the can.

The valve stem is moved back to close the valve 145 under a spring action and the valve is opened 20 by the energizing of a solenoid 149 (Figs. 5 and 10) which is electrically associated with the drive shaft 71. A collet screw 151 connects the rear end of the valve stem to a link 152 which is carried on the end of a solenoid core 153.

25 Solenoid 149 is mounted in a bracket 155 which is secured on the side of the column 98. The solenoid core projects beyond the end of the solenoid and an expansion spring 156, located on the core, is confined between a core head 157 and the solenoid. As long as the solenoid is de-energized the spring 156 holds the valve 145 closed. Energizing of the solenoid overcomes the spring action and draws the core toward the left (Fig. 10) opening the valve.

30 35 The winding of the solenoid 149 is connected to a source of electric energy by a wire 158 (Fig. 5). This electric energy is diagrammatically indicated as a generator 159 and the other side of the generator is connected by a wire 161 to a switch 40 162. This switch is electrically connected to the other winding of the solenoid by a wire 163 and may be mounted, as shown, in a stationary position on the bearing bracket 73.

45 Switch 162 is formed with an actuating spring lever which carries a roller 164, this being a common form of electric switch. The roller 164 rides on the periphery of the cam 76 which is mounted on and turns with the drive shaft 71. As long as the roller 164 holds the switch lever 50 in the position shown in Fig. 5 current flows through the circuit and energizes the solenoid. At such a time the valve 145 is held open and the paraffin is discharging from the spray head.

55 A cam segment 165 is carried on the periphery of the cam 76 and when rotation of the latter brings this cam segment under the switch roller 164, roller and spring lever are lifted and the current is broken. This allows the spring 156 to 60 close the valve 145 and shut off the flow of paraffin from the spray head.

When the machine stops after each cycle of operation the cam segment 165 is directly under and remains in engagement with the switch roller so that no spraying takes place while a sprayed 65 can is being removed from the cradle and while a new can is being put into position for spraying.

The compressed air which is used in the spraying operation is brought into the machine by means of a supply pipe 171 (Fig. 5) and into an 70 air reservoir or chamber 172 formed below the bottom of the tank 101. This chamber is enclosed in a cylindrical wall 173 which may be an integral part of the bottom of the tank. The lower end of the chamber is closed by a plate 75 174.

The chamber 172 communicates with the lower end of a pipe coil 175 which is disposed within the tank 101 and the upper end of this coil is connected by a pipe 176 to a passageway 177 formed in the rear wall of the column 98. Passageway 177 communicates with the lower end of a vertical pipe or tube 178 (see also Fig. 10) and the upper end of the latter is threaded secured in the web 97.

A passageway 179 is formed in the web and 10 communicates with the upper end of the tube 178. An opening 181 is cut through the lower rear part of the spray head tube 96 and provides a communication between the passageway 179 and a chamber 182 disposed in the lower part of the 15 tube below its partition 121. Spaced inclined partitions 183, 184 are also joined to or are an integral part of the horizontal partition and these extend down and connect with the wall of the spray head tube, thus making the chamber 182 20 airtight.

A second horizontal pipe 188 (Figs. 10 and 11) is disposed inside of the tube 96 just beneath the partition 121 and this tube extends through the spray head in the same manner as the upper 25 pipe 131. The rear end of the pipe 188 passes through the partition 183 and extends into the chamber 182. Its forward end terminates in the spray head sleeve 132. A passageway 189 formed in the sleeve provides a communication between 30 the interior of the forward end of the pipe and the mixing chamber 138.

By means of these connections the compressed air coming into the apparatus and passing through the various passageways is delivered into 35 the same mixing chamber with the paraffin escaping from its pipe 131 and together the intermingled air and paraffin rapidly flow out, under the confined air pressure, through the passageways and openings 131, 135, 136.

40 Compressed air is also used to assist the flow of the paraffin from its reservoir 107 and into the mixing chamber 138 of the spray head. For this purpose a pressure is maintained on the upper surface of the paraffin confined within the 45 reservoir. Compressed air may be introduced through a supply pipe 191 (Fig. 5) which is threaded secured into the reservoir tank wall, the inner end of the pipe communicating with a port 192 formed in the flange 108 of the reservoir 50 and communicating with a head space 193 confined below the tightly sealed cover plate 109.

55 Provision is made for maintaining a constant heat for the paraffin from the time it leaves the reservoir 107 and until it leaves the pipe 131. This heating is effected by the circulation of water or other suitable fluid which passes around and along the path of travel of the paraffin so that the liquid condition of the coating material is maintained at all times while in the apparatus. In addition to this the compressed air passing through the coils 175 is also subjected to the heating influence of this circulating heating fluid and these features will now be considered in detail.

60 65 The circulation of the heating fluid may be assumed to begin in the tank 101 (Fig. 5) which is completely filled with the water or other fluid. This water may be supplied through a pipe 195 (Fig. 5) containing a service valve 196, the pipe 70 passing through the cover 99 and discharging directly into the tank.

The water is continually heated in the tank as by gas flames issuing from gas burners 197 located under the tank. To retain the heat within 75

the tank its side walls are insulated at 198, this insulation being suitably held in place by an outer lining 199.

The water fills the column 98 and when the 5 heated currents meet with the web 97 they circulate through a curved passageway 201 (Fig. 10) which is cut through the lower part of the web. The upper part of this passageway communicates with an opening 202 cut in the lower wall 10 of the spray tube 96 and water fills the lower part of the latter in front of the partition 183 and below the partition 121 this space constituting a lower chamber 203 in the spray head tube.

It will be observed by reference to Fig. 5 that 15 the compressed air coil 175 is completely surrounded by the water within the tank 101. This heats the coil and also the air flowing therethrough. The tube 178 and pipe 188 containing the compressed air are also surrounded by the 20 water which thus maintains and further heats the air up to the time it enters the mixing chamber 138.

The partition 121 terminates short of the rear 25 end of the spray sleeve 132 and this provides a space 205 (Fig. 10) at the center of the tube 96 which allows communication between the lower chamber 203 of the tube and an upper chamber 206 located above the partition. The heated water thus circulates through and fills the chamber 30 206.

The top wall of the tube 96 is cut through in 35 an opening 207 which is adjacent the partition 123 and this opening registers with a curved passageway 208 formed in the web 97 of the column 98, its upper end opening into the upper part of the column. The water completely fills the passageway and the column and the rising heat currents follow such a path.

The upper end of the hollow column communicates with an opening 209 which is cut in the bottom wall of the tank 106 and which opens the interior of the column to the interior of the tank. Further circulation of the heated liquid thus continues and includes water which fills the tank 106.

40 It will be observed that the tube 114 conducting the paraffin from its reservoir 107 is surrounded with this circulating heated water within the upper part of the column 98 and also that the pipe 131 is immersed in heated water within the 45 upper head chamber 206. This maintains a proper heat in the liquid paraffin during its passage into the mixing chamber 138. The heated water completely fills the tank 106 and surrounds the reservoir tank 107 and this imparts its heat to the paraffin within the reservoir. A return pipe 50 211 joins the tank 106 with the tank 101 and completes the circulatory system of the heating medium.

In this manner as heat is applied to the water 55 within the tank 101 convection currents of heat are transmitted through the various passages to the various parts of the spray head 95 and to the tank 106. In this way the desired temperature is imparted to the paraffin and also to the compressed air so that the heated mixture of the two issues from the spray head in the coating operation. During the time the paraffin discharge is 60 shut off the heated air still issues from the spray head and this cleans out and keeps the perforations 136 heated and free of foreign materials. The various perforations 136 (Fig. 10) are so located in the spherical tip 133 of the spray head that jets of coating material may be directed as required and ejected with some force to all portions of the interior walls of the can during its 65

movement over the spray head 95 and during the reversed movement as it is being withdrawn from the spray head.

In addition to this back and forth movement of the can, the rocking movement imparted to the cradle at the beginning of each travel stroke also rocks the can. This insures a more even coating on the inside can walls by permitting a slight flowing action of the paraffin while it is still sufficiently warm and sufficiently liquid. The 10 paraffin discharge from the spray head consumes a major portion of the time cycle of operation of the machine.

This time of spraying is determined by the extent and the position of the cam segment 165 15 (Fig. 5) relative to the cam 76 and may be so arranged as to start the spraying action as soon as the tip of the spray head 95 first enters into the nozzle B of the can. Spraying continues throughout the entire moving of the can over 20 the spray head and also in the reverse movement until the can is about ready to leave the spray head. This latter position is about that shown in Fig. 9. Such a setting insures coating of the 25 inside of the nozzle as well as the interior of the can.

The interiorly sprayed can may then be removed from the spraying machine for subsequent cooling. Figure 3 of the drawings illustrates one form of cooling machine which not only cools the 30 can quickly but also insures an even setting of the interior coating by turning the can during cooling.

The sprayed can is placed in a rotatable frame 215 of the cooling machine, this being done by 35 hand or in any other suitable manner. In the cooling machine the can is preferably turned on its longitudinal axis and is so rotated between streams of cool air, such air currents being indicated in the drawings by arrows. This air may be projected from openings 216 formed in spaced air conducting pipes 217 arranged on opposite sides of the can.

The rotatable frame 215 includes a rear flange 218 and a spaced front flange 219, the two flanges 40 being separated by spacer tubes 221. Flanges and tubes are held together in a rigid frame by tie rods 222 passed through the tubes. The cans are inserted endwise into this frame, the front flange having an opening for that purpose.

The rotatable frame 215 of the cooling machine 45 is located in a housing 223 which also carries rollers 224 mounted on shafts 225 journaled in bearings 226 carried by the housing. These rollers are properly grooved to retain the rotatable 50 frame against longitudinal displacement, the flanges 218, 219 resting directly on and being supported by the rollers.

The rollers are also rotated in any suitable manner and their rotation is imparted to the 55 rotating frame 215. It will be understood that the frame is stopped during the insertion and the removal of a can. The starting and stopping of the rollers 224 and with them the rotating frame 215 may be controlled by the operator in any 60 suitable manner as by actuation of a suitable clutch treadle 227. Inasmuch as many well known types of driving mechanism and treadle clutch devices may be satisfactorily used on the cooling machine it is believed that further details 65 and further description of these features are unnecessary for the purposes of the present invention.

It is thought that the invention and many of its attendant advantages will be understood from 70 75

the foregoing description, and it will be apparent that various changes may be made in the form, construction, and arrangement of parts of the apparatus mentioned herein and in the steps and 5 their order of accomplishment of the process described herein, without departing from the spirit and scope of the invention or sacrificing all of its material advantages, the apparatus and process hereinbefore described being merely a preferred 10 embodiment thereof.

I claim:

1. In a container spraying and coating machine, the combination of a heated reservoir for containing liquid coating material which is solid 15 at normal room temperatures, a spray head for directing said heated and liquefied coating material onto a container, means for conducting said coating material in fluid condition to said spray head, pressure means for ejecting said material 20 from said spray head onto said container, means for imparting relative axial movement to said container and spray head during the spraying operation, and means for oscillating said container on a transverse axis thereof to insure uniform 25 distribution of the sprayed coating thereon.

2. In a container spraying and coating machine, the combination of a heated reservoir for containing liquid coating material which is solid at normal room temperatures, a spray head for 30 directing said heated and liquefied coating material onto a container, means for conducting said coating material in fluid condition from said reservoir to said spray head, thermo-syphonic means for heating said coating material while in said 35 reservoir and during its passage through said conducting means to said spray head, and pressure means for ejecting said heated material from said spray head onto said container, and means for imparting axial and oscillatory movement 40 to said container relative to said spray head during the spraying operation.

3. In a container spraying and coating machine, the combination of a heated reservoir for containing liquid coating material which is solid 45 at normal room temperatures, a spray head for directing said heated and liquefied coating material onto a container, means for conducting said coating material in fluid condition to said spray head, means for mixing compressed air with said liquefied material, thermo-syphonic means for heating said coating material while in said reservoir and during its passage through said conducting means to said spray head and for pre-heating said air before mixing with said coating 50 material, said spray head directing said mixture onto said container under the pressure supplied by said compressed air, and means for imparting axial and oscillatory movement to said container relative to said spray head during the spraying 55 operation.

4. In a container spraying and coating machine, the combination of a reservoir for containing a coating material which is solid at normal room temperatures, heating means enclosing said reservoir for liquefying said coating material, devices for holding a nozzle container in position for coating, a spray head for directing said coating material against the interior of the held container, while the spray head extends 65 through the container nozzle, means for conducting said coating material from said reservoir to said spray head while maintaining it in liquid form, pressure means for ejecting said coating 70

material from said spray head to coat the container interior, and means for rocking said container on its transverse axis and relative to said spray head during said coating operation.

5. In a container spraying and coating machine, the combination of a heating reservoir for containing liquid coating material which is solid at normal room temperatures, means for heating said reservoir, a stationary spray head for receiving coating material from said reservoir, devices 10 for moving a nozzle container over said spray head and into spraying position with the latter extending through said nozzle and inside of the container, means for ejecting said coating material from said spray head while it is inside of the 15 container, and means for oscillating the container on its transverse axis during the coating operation.

6. In a container spraying and coating machine, the combination of a heating reservoir 20 for containing liquid coating material which is solid at normal room temperatures and which is liquefied by heat while in said reservoir, means for heating said reservoir, a stationary spray head for receiving coating material from said 25 reservoir, devices for moving a nozzle container over said spray head and with the latter extending through said nozzle and inside of the container, means for ejecting and atomizing said coating material from said spray head while it 30 is inside of the container, and means for moving the container during the coating operation and rocking it to insure even coating of all of its interior.

7. In a container spraying and coating machine, the combination of a heating reservoir for containing liquid coating material which is solid at normal room temperatures and which is liquefied by heat while in said reservoir, means for heating said reservoir, a spray head for receiving 40 coating material from said reservoir, devices for imparting relative movement between a nozzle container and said spray head to the end that the latter extends through said nozzle and inside of the container, means for ejecting and 45 atomizing said coating material from said spray head while it is inside of the container, and means for moving the container during the coating operation and rocking it to insure even coating of all of its interior.

8. A method of spraying and coating containers which comprises heating the area to be sprayed, heating a coating material to liquefy it, spraying said liquefied coating material on said heated area, the while oscillating said container 55 to cause an abrupt change of movement in the area being sprayed while the heated coating material is in liquefied form to permit the deposited material to flow over the coated surface whereby to evenly distribute the same, and cooling 60 said heated and sprayed area to solidify said coating material.

9. A method of spraying and coating containers which comprises spraying the container with a heated coating material, simultaneously oscillating said containers on a transverse axis thereof and in opposite directions to cause an abrupt movement of the area being sprayed to direct a flow of the sprayed material over the coated surface whereby to evenly distribute the thickness 70 of the coating material over the sprayed area, and then cooling the sprayed containers.

JOHN F. PETERS.
